ZOO TOY

Michael Langieri, Butler, N.J., assignor to Questor Corporation, Toledo, Ohio

Filed Oct. 2, 1972, Ser. No. 294,422

Term of patent 14 years

Int. Cl. D21—01

U.S. Cl. D34—15 A

Fig. 1.

Fig. 2.

Fig. 3.

FIG. 1 is a perspective view of a zoo toy showing my new design;

FIG. 2 is a left-side elevational view; and
FIG. 3 is a top plan view.

I claim:

The ornamental design for a zoo toy, as shown.
